US0D1026297S

(12) **United States Design Patent** (10) **Patent No.:** **US D1,026,297 S**
(45) **Date of Patent:** **** May 7, 2024**

(54) **SET OF LENSES**

(71) Applicant: **Dandan Tan**, Ziyang (CN)

(72) Inventor: **Dandan Tan**, Ziyang (CN)

(**) Term: **15 Years**

(21) Appl. No.: **29/865,230**

(22) Filed: **Jul. 15, 2022**

(51) **LOC (14) Cl.** **26-05**

(52) **U.S. Cl.**

USPC **D26/123**

(58) **Field of Classification Search**

(57) **CLAIM**

The ornamental design for a set of lenses, as shown and described.

DESCRIPTION

FIG. 1 is a perspective view of a first lens of a set of lenses showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second lens of the set of lenses;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

1 Claim, 16 Drawing Sheets
